Primary Examiner — Elizabeth A. Albert(74) *Attorney, Agent, or Firm* — Susan Paik, Esq.(57) **CLAIM**

The ornamental design for a tape dispenser, as shown and described.

DESCRIPTION

FIG. 1 is a front perspective view of a tape dispenser, showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof; and,

FIG. 8 is a front perspective view of the tape dispenser of FIG. 1 showing rolls of tape held therein.

The broken lines in the drawings are included to show features and articles that form no part of the claimed design.
